SWITCH

Ernest H. Jacobs, River Forest, Ill., assignor to
 Electrical Engineers Equipment Co., Melrose
 Park, Ill., a Corporation of Illinois

Application March 31, 1928. Serial No. 266,167

9 Claims. (Cl. 200—48)

My invention relates to electrical switches, more particularly the outdoor gang operated type such as are commonly employed for power disconnect purposes. While the invention is particularly applicable to this service, it is not intended to limit it to that use.

The preferred embodiment of this invention provides a switch of minimum structure, securing good contact when the switch is closed, easily operable to open or close, and which provides a large separation of the contacts on opening.

For outdoor service the contacts of the switch must be protected against weather conditions, and one of the conditions presenting the greatest difficulty is the accumulation of sleet on the contacts. It has been customary heretofore to house one or both of the contacts under a shelter known as a sleet hood for the purpose of avoiding freezing of the contacts together so that they cannot be separated when it is desired to open the switch and also to minimize the difficulties of closing the switch under conditions where sleet would tend to accumulate on one or more parts.

According to the present invention I provide stationary floating contacts and a movable plunger rigid contact, although it is within my invention to reverse the relation of these parts.

The preferred embodiment presents a minimum of material and labor in construction, resulting in a device of low cost but with highly satisfactory operating characteristics.

Now in order to acquaint those skilled in the art with the manner of constructing and operating the device embodying my invention I shall describe in connection with the accompanying drawings a specific embodiment of my invention.

In the drawings

Fig. 1 is a side elevational view of a sleet hood crank switch shown in closed position, with the dotted lines showing the open position of the parts.

Fig. 2 is an enlarged side elevational view of the stationary contacts with the side plate of the sleet hood removed.

Fig. 3 is a horizontal section taken on the line 3—3 of Fig. 2 to illustrate the construction of stationary contacts and the sleet hood, and Fig. 4 is a section on line 4—4 of Fig. 1.

Referring to Fig. 1, the common base member 1, which is preferably a channel bar in inverted position, supports at its opposite ends stationary insulators 2 and 3. The stationary insulator 3 has its pedestal 4 mounted directly on the inverted web of the channel bar 1, whereas the

insulator 2 has its pedestal 5 mounted upon a spacing block 6 that in turn rests upon the frame member 1.

While in Fig. 1 the elements for a single phase only appear, it is to be understood that directly back of the switch shown in Fig. 1 there are placed two other identical units for a three phase line, the channel bases 1 being suitably connected together by a framework on which the gang switch is mounted.

The cap 7 of insulator 3 contains a base and terminal member 8 bolted thereto. This base and terminal member 8 carries a pivot lug 9 for receiving a pivot pin 10. The base and terminal member 8 also provides a laterally extending arm 11 to which there is connected a terminal lug 12 of the phase conductor 13. The phase conductor 13 is gripped to the arm 11 mechanically as by means of the U bolt 14. The flattened part of the terminal lug 12 is bolted to the arm member 11 as by means of the bolts 16 with the ends of two flexible ribbons 17 disposed between it and said arm 11.

The stationary insulator 2 has a cap member 18 which supports a bracket member 19 thereupon. This bracket member 19 is shown on an enlarged scale in Fig. 2. It has a laterally extending arm 20 to which by means of the U bolt 21 the line phase conductor 22 is mechanically bolted. The line phase conductor is electrically connected to a terminal lug 23, the flattened end of which extends upward at an angle as indicated at 24 parallel to an angularly disposed portion 25 of the bracket member 19. Bolts 26 extend through the flattened part of the terminal lug at 24 and through the bracket portion 25, and these parts clamp between them the lower ends of the flexible leads or copper ribbons 27, 28 to make connection between the line conductor 22 and the stationary contacts 29 and 30 which are housed and mounted in the sleet hood 31 on top of the bracket 19.

The sleet hood 31 comprises a chamber substantially closed on all sides except that which faces towards the other line phase conductor 13. On this side it has an opening 33 provided with tapered guiding surfaces 34 and 35 and an overhanging porch and roof 36. Preferably the main part of the sleet hood 31 is cast integral with the bracket 19 with one side thereof left open to be closed by cover plate 37 held in place by the bolts 38 and 39. Contact members 29 and 30 comprise stampings of sheet copper or brass with flaring front ends 40 and 41 lying immediately back of the tapered inlet opening 33 in such a po-

sition as to receive readily and guide into place between them a contact member 42 which is preferably a solid copper cast bar. The forward end 43 of the bar 44 is suitably beveled and milled or ground off parallel so as to provide flat surface contact with the flat central parts of the contacts 29, 30. The rear ends of the contacts 29 and 30 are provided with laterally extending flanges 45 and 46 formed by bending of the body 10 of the sheet metal contacts 29 and 30 at right angles to the main flat portions thereof. The upper ends of the copper ribbons 27 and 28 are clamped to the flanges 45 and 46 as by means of clamping plates 47, 48 and bolts 49, 50. The contacts 29 and 30 have upwardly extending lugs 52 and downwardly extending lugs 53 pierced for passage therethrough of the supporting and guiding bolts 38 and 39. The bolts 38 and 39 have coil springs 54 and 55 mounted thereupon, these 15 springs being held under compression whereby the contact members 29 and 30 are forced towards each other by pressure exerted upon the ears or lugs 52 and 53. The bolts 38 and 39 are spaced far enough apart to permit the passage between 20 them of the forward end 43 of the contact arm 44.

The forward ends of the contacts 29 and 30 are pressed towards each other by compression springs 56 and 57 mounted upon short studs 58 and 59. These springs 56 and 57 are under compression, 30 and they force the contact members 29 and 30 towards each other so as to make good contact with the movable contact member 43.

It will be observed that the pressure of the springs is applied to the contacts 29 and 30 at 35 three points so that these contacts may have substantially universal motion of limited degree to adapt themselves to the sides of the movable contact member 43. Also due to the pressure being applied at three points and the contacts held at 40 two points against rocking up and down or moving back and forth an inexpensive universal mounting with evenly applied pressure is secured. A relatively large amount of sidewise motion or play is permissible due to the fact that the springs 45 are all under balanced compression so that lack of alinement angularly or bodily even in considerable amount does not prevent the securing and maintaining of excellent contact between the stationary and movable contact members.

50 Due to the overhanging porch 36 of the hood 31 sleet is excluded and yet ample opportunity for the contacts to come into engagement is afforded.

The bar 44 is hinged at its rear end on a pin 61 55 which pin is supported at opposite sides of the bar 44 on a pair of links 62. Instead of employing a pair of links a single link may be utilized for the reason that the bar 44 secures an independent guiding motion from a movable insulator 63 as will be described more at length later.

The bar 44 has laterally extending lugs 64 60 at each side and to each of these lugs there is bolted as by means of the bolt 65 the upper end of the corresponding copper flexible ribbon 17.

The lower ends of the links 62 are hinged on 65 the pin 10. It will be observed that the upper end of the link 62 rises about its center 10 as the switch is moved to the open position indicated in dotted lines.

The rocking insulator 63 has its pedestal 67 70 clamped by means of a suitable split clamp to the hollow squared shaft 68. The hollow squared shaft 68 comprises a piece of tubing rolled into square form, and it is supported in bearings 69

through the intermediary of journal blocks 70 which preferably are brass cylinders with suitable rectangular openings therethrough for receiving the squared shaft 68. The bearing pedestal 69 has a sleeve 71 of larger size than the brass cylinder 70, and it is adapted to receive Babbitt metal or the like. To prevent endwise shifting of the hollow square shaft collars may be clamped upon opposite sides of the bearing pedestal 69 to the said squared shaft. 80 85

Squared shaft 68 in turn is connected as by a suitable split clamp with the operating arm 72, it having a suitable quadrant 73 at its outer end provided with a series of holes for the attachment of a pipe clevis 74 threaded and clamped upon the upper end of an operating pipe or rod 76. This operating rod 76 at its lower end is connected with an arm 77, and it in turn is pivoted as by means of pin 78 on an operating quadrant 79 supported on a pivot 80. Pivot 80 is a pin mounted in the bracket 81. The bracket 81 is provided with locking hole 82 adapted to register with a hole in the lug 83 formed on the operating quadrant 79. A suitable pin slotted at its end to receive a padlock may be passed through the registering hole in the bracket and arm to lock the switch in closed position. 90 95

The quadrant 79 has another hole 84 adapted to register with the hole 82 for locking the switch in open position. 100 105

A handle member 86 is connected to quadrant 79 for the purpose of throwing the switch to open or closed position.

The insulator 63 has a cap 87 on which there is bolted a bracket 88, this bracket being bifurcated at its upper end to embrace the sides of the contact bar 44, a pivot pin 89 being passed through the upper end of the bracket and through the contact arm 44. 110 115

The free end of the contact bar 44 is controlled by the movement of the bracket 88 about the squared shaft 68 as a center, and it will be seen that within the limits of motion indicated between the full lines in Fig. 1 and the dotted lines therein the outer end 43 of the arm 44 moves from a substantially horizontal position to a position which is more nearly vertical. The relation of the lengths of the arms 62, 44 and the effective length of the bracket 88 are essential to secure this action. It will be observed that the bifurcated bracket 88 is split down to substantially the base thereof so that the end 43 of the arm 44 passes within said bracket 88 when the switch is in open position as indicated in dotted lines in Fig. 1. 120 125 130

By changing the length of the link 62 or the effective length from the pivot 89 to pivot 68 of the operating insulator the contact portion 43 may be plunged below horizontal position or above horizontal position, but I prefer substantially the relation of the parts shown in the drawings whereby the contact portion 43 enters the stationary contact jaws 29 and 30 in substantially horizontal position. 135 140

The stationary arcing horn 86 shaped somewhat like a reversed numeral 4 has its stem 87 secured by clamp 88 to the bracket 19. This arcing horn 86 extends sufficiently far forward to permit the movable arcing horn 90, which is fastened at the side of the bracket member 88 as shown in Fig. 1, to maintain contact as long as is necessary to protect the current carrying contacts from injury by any arc which may be formed upon opening up the switch. 145 150

Since the contact arm 44 which is relatively

wide and heavy is closely guided between the two arms of the bracket 88 on the pivot 89, a single controlling link 62 is sufficient to govern the path of the rear end of said arm.

5 It will be observed that in the form shown the stationary contact is disposed a substantial distance vertically above the base 1, and that the pivot 10 for the controlling link 62 is disposed at a point considerably lower. The pivot 10 for the rocking insulator is disposed about half way between the two stationary insulators, being perhaps a trifle nearer the insulator 2 than the insulator 3.

15 As shown in Fig. 1, the length of the controlling link 62 is less than the length of the operating link which includes the bracket 88. The length of the arm 44 from its pivot 61 to its front operating portion 43 is about the same as the length of the link 62, and the effective length between 20 pivots 89 and 61 while greater than the distance between the pivot 89 and the end of the contact 43 is less than the length of any of the other links or distance between operating pivots. The distance between the pivot pin 10 and center 25 of shaft 68 in the form shown is approximately the same as the length of the controlling arm 62. While I have explained these dimensions and proportions in connection with the specific form shown, it is to be understood that variations 30 between these proportions are permissible where variations in action may be tolerated, all without departing from the essential features of my invention.

35 The quadrilateral comprising the link 44, link 42, a line drawn from the stationary pivot 10 to the stationary pivot 68, and a line from the pivot 68 to the pivot 89 constitutes what is in this patent application referred to as quadrilateral linkage. In this quadrilateral linkage the 40 line drawn from the stationary pivot 10 to the stationary pivot 68 constitutes a "fourth" link which is of course always stationary while the other three links are movable.

45 When the switch is in open position the rocking insulator 63 leans back toward the insulator 3 so that the arcing horn 90 together with the stationary arcing horn 86 provides divergent members suitable for breaking an arc if the same should persist by the natural rise of the arc on 50 the horns.

55 The striking distance between the live parts of the switch when the switch is open is unusually high. This is secured first by the backward tilt of the insulator 63 when the switch is open and also by the disposal of the sleet hood and its contained contacts vertically above the level of the insulator cap 87 so that the forward projection of the sleet hood and the contacts therein does not cut down the striking distance. The 60 folding back of the switch arm 44 as shown in dotted lines removes any projecting parts from the movable member, thereby assisting in securing this maximum opening when the parts are thrown to the open position.

65 When the rocking insulator is actuated to close the switch, the forward end 43 of the contact arm 44 moves along a path 90 to its full closed position. It is to be noted that the contact making portion of the switch arm approaches the 70 housing 31 from below the housing and enters the housing by a substantially horizontal movement. As a result it is possible to provide a housing such as is shown at 31 having a top portion which is closed and having an open side through 75 which the contact making portion of the blade

passes into the housing. The top of the housing overhangs the open side thereof thereby protecting the contacts against the entrance of moisture or other foreign material from above. This would not be possible if the contact making portion 43 were to move into engagement with the contact in the housing from a direction above the housing. The portion of the curve 90, which curve represents the path of motion of the free end of the contact making arm 43, that extends from a point slightly in advance of the housing up to the point on the curve representing the full closed position of the switch very nearly approaches the arc of a circle having a center at the point indicated at 91. This point 91 is, as is to be noted, directly vertically below the contact making arm 43 when the same is in its closed position. Hence, in so far as the contact making or breaking action is concerned, the contact making portion 43 moves as though the insulator 63 were pivoted at the point 91 with the contact arm 43 rigid with the insulator. This is a desirable type of motion and my improved link mechanism provides this type of motion in a manner by far superior to the manner of obtaining this motion by using a larger rocking insulator pivoted at 91.

90 When the switch is in the open position it is to be noted that the contact arm 43 lies between the tines of the bifurcated bracket 88. Due to the fact that this bracket embraces the sides of the contact making portion 43 of the switch arm there is appreciably less chance of this portion becoming heavily coated with ice or sleet during 100 the time that the switch remains in its open position, with the result that the switch can always be actuated to establish good electrical connections with the contact within the housing 31, a feature which would not be possible if one or 105 the other of the contacts were heavily coated with ice or sleet.

110 As previously pointed out, the length of the portion of the link 44 between the pivot pin 61 and the pivot pin 89 is less than the distance 120 between the pivot pin 61 and the pivot pin 10. This is of considerable importance during the switch opening operation. When the switch is in the position shown in dotted lines in Figure 1, the rocking insulator has approached its limit of permissible movement. Should an additional pull be exerted upon the operating pipe 76 tending to further rock the rocking insulator in a clockwise direction as seen in Figure 1 this insulator will move further a slight amount whereupon the links 62 and 44 will come into a position of substantial alignment. This position will be reached after a very slight turning of the rocking insulator from the position as shown in the drawings. After the rocking insulator reaches 125 this position it is not possible to further turn the same since the links 62 and 44 will hold the rocking insulator against further movement in a clockwise direction. This is of considerable importance from several points of view. In the first place it prevents the actuation of the switch to such an extent that the rocking insulator 63 or the bracket 88 mounted thereon will be jammed against the stationary insulator 3. Such action 130 might crack one or the other or both of the two insulators. In addition, should the operating mechanism break when the switch is in its open position, or should it be necessary to remove the operating rod or any portion thereof, the rocking insulator would not fall against the stationary insulator. If the links 44 and 62 were of 135

140

145

150

different proportions so that the link 44 is longer than the link 62 then the link-work would not tend to limit the swing of the rocking insulator and under such conditions this insulator might swing or fall against the stationary insulator 3 and it would certainly render the reassemblage of the operating mechanism including the clevis 74 and the pipe or rod 76, or any of the lower operating parts that have been disassembled, more difficult due to the fact that in the final assembly the operator would have to be supporting the rocking insulator as he is assembling the parts. This difficulty is aggravated by the fact that switches of the kind here contemplated are generally gang operated there being three or more such switches mounted on a common shaft and it is the weight of all of these switches that would have to be supported by the operator in the final reassembly of the apparatus.

20 I claim:

1. In combination a bracket member having a base for mounting the same upon an insulator, a sloping side wall, a sleet hood mounted upon the upper end of the same, a pair of contact jaws mounted in the sleet hood having flexible leads extending down into engagement with said sloping member, a terminal lug having a flattened portion clamped upon said flexible leads against said sloping member.
2. In combination a bracket member having a base for mounting the same upon an insulator, a sloping side wall, a sleet hood mounted upon the upper end of the same, a pair of contact jaws mounted in the sleet hood having flexible leads extending down into engagement with said sloping member, a terminal lug having a flattened portion clamped upon said flexible leads against said sloping member, a laterally extending strain arm, and clamping means for a line conductor on said strain arm, said terminal lug having a tubular socket in alignment with said clamping means.
3. In a switch, a bracket having a sloping clamping member, contacts mounted on the upper end of the bracket and having flexible leads extending into engagement with said sloping member, and a terminal member having a flattened portion engaging said flexible leads and clamped to the sloping member.
4. In an electric switch, the combination with a rocking insulator mounted on a fixed pivot, means for rocking the insulator, a bifurcated bracket mounted on the insulator, a switch blade pivotally connected to said bracket between the arms thereof to swing in the same plane as the insulator, and link means for swinging the blade about its pivot upon the opening movement of the insulator into a position between its pivot and the insulator, the contacting end of the blade lying between the arms of the bracket, the blade being moved into a position such that the striking distance to the blade is approximately the same as the striking distance to the bracket.
5. A disconnect switch comprising a supporting insulator, a contact mounted thereon, a rocking insulator mounted adjacent the first named in-

sulator and rockable towards and away from the same, a bifurcated bracket mounted on the rocking insulator, a switch arm pivotally mounted on the bracket and closely guided between the arms thereof and including a contact making portion movable into and out of engagement with the contact upon movement of the rocking insulator, and means effective as the rocking insulator moves towards its switch open position to swing substantially the entire contact making portion of the switch arm into a position between the closely guiding arms of the bracket.

6. In an electric switch, in combination, a movable contact member including a contact making portion, means for shielding the foremost portion of the sides of said contact making portion from sleet when the contact is in its switch-open position, said means comprising contact supporting means, and means for moving said contact making portion out of said shielding means when said contact member moves to its switch-closed position.

7. In an electric switch, in combination, a supporting base, a bifurcated link pivoted on said base, a contact member including a contact making portion pivoted on said link, said contact making portion being adapted to fit closely between the arms of said link, and means effective as said link and contact member move into their switch-open position to swing the foremost end of said contact making portion into a position between the arms of said link.

8. In an electric switch, a movable contact making member including a contact making portion, a second contact member with which said contact making portion engages in its switch closed position, means for shielding said second contact member from sleet, means for supporting and shielding said contact making portion from sleet when said contact making portion is in its switch-open position, said last means including means shielding the contacting tip of the contact making portion, and means for moving said contact making portion into sleet shielded relation with said supporting means when said contact making portion moves to its switch-open position.

9. In an electric disconnect switch, in combination, a stationary contact, a sleet hood enclosing the contact and having a side opening, the top of said hood overhanging the contact, a movable switch arm including a contact making portion adapted to be plunged beneath the overhanging top in a substantially horizontal direction into engagement with the contact to close the switch, and means for imparting said plunger movement to the switch arm, said means comprising a quadrilateral linkage including a part of the switch arm and a bifurcated link pivoted to said switch arm, said switch arm and link being so arranged as to swing the foremost end of said contact making portion into sleet shielded position between the arms of said link when said switch arm moves to its switch-open position.

ERNEST H. JACOBS.
